UNITED STATES PATENT OFFICE.

EDMUND P. FOWLER, OF NEW YORK, N. Y.

NASAL DOUCHE.

1,185,649.

Specification of Letters Patent. Patented June 6, 1916.

Application filed December 10, 1909. Serial No. 532,355.

To all whom it may concern:

Be it known that I, EDMUND P. FOWLER, a citizen of the United States, residing at the city of New York, in the county and State 5 of New York, have invented certain new and useful Improvements in Nasal Douches, of which the following is a full, clear, and exact specification.

My invention relates to improvements in 10 douching and spraying devices, and the same has for its object to provide a simple, efficient and reliable nasal douche or sprayer which is adapted to be operated by blowing into the body thereof to create an air pressure 15 sure upon the fluid therein.

Further, said invention has for its object to provide a device which is so constructed that when the nozzle thereof is properly in 20 position within the nose, the aperture in the body thereof will be in position to be engaged by the lips of the operator.

Further, said invention has for its object to provide a device which shall be easy to operate, convenient to handle, and composed 25 of the smallest number of parts possible so as to be readily kept clean.

To the attainment of the aforesaid objects and ends, my invention consists in the novel details of construction, and in the 30 combination, connection and arrangement of parts hereinafter more fully described and then pointed out in the claims.

In the accompanying drawings wherein like numerals of reference indicate like 35 parts, Figure 1, is a side view showing one form of douche or spraying device constructed according to and embodying my said invention; the same being shown in the hand of the operator and in position for 40 use; Fig. 2, is a top view of the atomizer; Fig. 3, a front view thereof; Fig. 4, a section taken on the line 4—4 of Fig. 3, and Fig. 5 is a detail sectional view showing a modified construction.

45 In said drawings 10 designates a douche or spraying device formed of glass, or other suitable material comprising a bulbous receptacle or body portion 11 having an upwardly projecting tapering nozzle 12, and 50 within said receptacle or body portion 11 is arranged a tube 13 which is secured at its upper end to the end of the nozzle 12 and provided adjacent to said end with small apertures or foramina 14. The lower end

of said tube 13 is curved and extends to a 55 point adjacent to the bottom of the receptacle or body portion 11.

The receptacle or body portion 11 is provided at one side at a point directly below the end of the nozzle 12 and in a vertical 60 plane with the end thereof (Fig. 4) with an aperture 15 having a flange 16 surrounding the same and extending outwardly therefrom to form a mouth piece, which also serves as a means for the introduction of 65 fluid into said receptacle 11.

In the modification illustrated at Fig. 5 the receptacle or body portion 20 is constructed essentially as hereinabove described, except that in this instance the end of the 70 nozzle 21 is open, and provided along its outer surface adjacent to said end with screw threads 22, and upon said threaded end is fitted a cap 23 to which is secured a tube 24 having its free end extending downwardly into said receptacle or body portion 20. 75

The operation of the device is the same in both constructions. To operate the same it merely becomes necessary to fill the body 80 portion or receptacle to a point just below the lower edge of the aperture 15, and insert the nozzle 12 within the nostril, as shown at Fig. 1. When the nozzle 12 is properly in position within the nostril the flanged-mouth piece of the aperture 15 will be in position to be engaged by the lips of the operator, and by forcing air into the receptacle 11 the fluid therein will be caused to rise in the tube 13 and issue from the upper 85 end thereof. Where no perforations are provided in the upper end of said tube the fluid will be discharged in the form of a stream, but where apertures or foramina 14 90 are provided in the upper end of said tube the stream of fluid as it issues from said tube will be broken up or atomized, and then forced into the nostril. Any fluid 95 which may pass from the nozzle downwardly upon the outer surface of the receptacle will be prevented from contacting with the lips or mouth of the user owing to the arrangement and construction of the flanged mouth-piece surrounding the opening in the side of said receptacle.

100 It will, of course, be understood that alterations in the shape of the receptacle or body portion of the device may be made 105

without changing the relative positions of the nozzle and mouth-piece.

Having thus described my invention, what I claim and desire to secure by Letters 5 Patent is:

1. A device of the character described, comprising a receptacle having an opening in the side thereof, an inclined nozzle portion extending upwardly from the top of 10 said receptacle and having its end terminating in a vertical plane above the opening in the side of said receptacle, and a delivery tube having its open upper end secured to the end of said nozzle and the remainder of 15 said tube free from said nozzle extending downwardly into said receptacle, substantially as specified.

2. A device of the character described, comprising a receptacle having an opening 20 in the side thereof, a nozzle projecting from the top of said receptacle, and a tube having its open upper end secured to said nozzle and provided adjacent to its upper end with

apertures, and its other end extending downwardly into said receptacle.

3. A device of the character described, comprising a receptacle having an opening in the side thereof, and a flanged mouth 25 piece surrounding said opening, an integral tapering upper portion forming a nozzle 30 having its end arranged above and in a vertical plane with the opening in the side of said receptacle, screw threads provided upon the end of said nozzle, a cap adapted for 35 securing to the threaded end of said nozzle, and a tube having its upper end secured to said cap, and its lower end extending downwardly into said receptacle, substantially as specified.

Signed at the city of New York, in the 40 county and State of New York, this 3d day of February, nineteen hundred and nine.

EDMUND P. FOWLER.
